Attorney

UNITED STATES PATENT OFFICE.

ALFRED G. F. KUROWSKI, OF BROOKLYN, NEW YORK, ASSIGNEE TO UNDERWOOD TYPEWRITER COMPANY, OF NEW YORK, N. Y., A CORPORATION OF DELAWARE.

TYPEWRITING MACHINE.

Application filed September 16, 1925. Serial No. 56,617.

This invention relates to tally-sheet feeding devices for typewriting machines, and may be advantageously used in grocery and other stores for making a tally of the orders 5 to be delivered by each driver. The device may be mounted at one end of a typewriter platen, so as to leave the other end free for typing thereon the usual customer sales slips at the same time a tally of them is made; 10 the sales slips and the tally-sheets being line-spaced and typed independently of each other.

Provision is made in the present invention of a feed-roll supporting frame mounted above the right end of the platen of a typewriting machine on a sleeve over a stiff rod, the latter being held at its two ends in brackets mounted on the carriage side frames. A stationary rotatable feed-roll is mounted in said frame above said platen and not engaging the same. A swing- 15 ing feed-roll is mounted for engagement against the top of the stationary feed-roll in the ends of two arms pivoted to said frame. A star-wheel is mounted on the shaft of the stationary feed-roll, and upon depression of the usual feed-roll-release lever, is rotated by engagement with a pawl-member which is pivotally fastened to the 20 lower end of the usual link-member attached to the rear end of said lever. The usual feed-rolls are omitted under the right end of the platen, and a tally-sheet around this end engaged between said upper feed-rolls may be line-spaced upon movement of 25 said star-wheel without revolving the platen. To permit characters to be typed near the top edge of the tally-sheet, a roll is mounted in the ends of two arms pivoted to said feed-roll frame, and is arranged to hold the sheet against the platen a short distance above the printing line. This roll may be swung 30 upwardly out of the way when not in use.

Other features and advantages will hereafter appear.

In the accompanying drawings,

Figure 1 is a fragmentary front elevational view of an Underwood typewriting machine having my invention applied thereto.

Figure 2 is a partial end view of the same shown partly in section.

Figure 3 is a cross-section along the line 3--3 of Figure 1.

Figure 4 is a fragmentary end view of the

invention in place on the carriage of an Underwood typewriting machine shown partly in section. The front tally-sheet holding roll is shown in its upper position.

Figure 5 is a fragmentary plan view of the right-hand portion of the carriage in an Underwood typewriting machine with the tally-sheet feeding device in place.

A platen 10 may be mounted on shaft 11, journaled in a carriage side frame 12 of an Underwood typewriting machine. A paper table 13 having an apron extension 14 is arranged between the said frames. Feed-rolls 15 and 16 are mounted only under the left-hand portion of the platen 10 on the 60 usual feed-roll rods, not shown. The feed-rolls may be thrown against and away from the platen by manipulation of a feed-roll release lever 17 which carries a link 18 at its rear end, the latter being connected with an arm 19 on a cam shaft 20, which is arranged to move locking arms, not shown, which arms support the feed-rolls 15 and 16.

For mounting the tally-sheet feeding device, brackets 21 and 22 may be fastened on the right and left side frames 12 and hold securely between them a stiff rod 23 over which may be slipped a sleeve 24 to whose ends may be securely fastened two plates 25, by riveting. The sleeve 24 will be of proper length to permit the right-hand plate 25 to be positioned adjacent the right-hand end of the platen 10 and have the left-hand plate 25 come a short distance beyond the left edge of a tally-sheet 26, used in the device.

A roll 27 engaging against the platen 10 for a purpose hereinafter explained, is mounted on a shaft 27^a held in the forward ends of two arms 28 and 28^a which have upwardly curved portions 29 and are fastened on the outer ends of a rod 30, the latter being journaled in the plates 25 and extending outwardly therefrom a short distance. A stationary feed-roll 31 is mounted a short distance above and not in engagement with the platen on a shaft 32 journaled in the left-hand plate 25 and in a floating bearing plate 33 attached to the right-hand plate 25 and in the bracket 21. A swinging feed-roll 34 is mounted for engagement with feed-roll 31 in the forward ends of two arms 35, which may be pivotally mounted on shouldered screws 36 threaded into the plates 25. Upwardly turned rear ends 37 of the arms 35 may be bent inwardly at 100

105 the arms 35 may be bent inwardly at 110

substantial right angles, and be connected by a bar 38 to form a swinging bail. To limit the upward swing of the feed-roll 34 (see Figure 3), two pins 39 are fastened 6 in the plates 25 in the rear slightly below screws 36.

- A star-wheel 40 having four points 41 and four cavities 42 may be fastened on the shaft 32, adjacent the inner side of the bracket 21. 10 A short inwardly and laterally projecting pin 43 may be fastened securely in each point 41. The tally-sheet 26 passes between the feed-rolls 31 and 34 and may be line-spaced by depressing the feed-roll release 15 lever 17. This action raises the link 18, which carries in its lower end a stud 44 to which is fastened a space-pawl 45, having its upper end arranged with an L-shaped concave cavity 46 for engaging under the 20 pins 43, one at a time. The pawl may rotate through one-fourth of a revolution a star-wheel 40 and a feed-roll 31. By providing a feed-roll of the proper size the tally-sheet 26 may be advanced one or more line-spaces 25 on the platen 10 for each depression of the lever 17. When the lever 17 is returned to normal position, the pawl 45 is lowered and the cavity 46 is pulled into engagement under the next lower pin 43 by action of a 30 spring 47, which has one end fastened to the pawl 45, and the other to a downwardly projecting arm 48 of the bracket 21. A roller 49 mounted on the forward end of a detent lever 50 for yielding engagement in the cavities 42 prevents the star-wheel from being rotated backwardly when the pawl is being lowered, and also properly lines up the feed-roll 31 when the latter is moved forward a slight amount too much or too little upon 35 depression of the lever 17. The roller 49 is always held in engagement with the star-wheel 40 by action of a tensile spring 51 fastened to the rear end of the lever 50 and to the bracket 21. 40 In one use of the tally-sheet feeding device, to make a record of groceries delivered by a driver, a narrow sales-slip 60, such as is commonly used in grocery stores, may be inserted from the rear around the left-hand portion of the platen 10 between the latter and the usual typewriter feed-rolls 15 and 16. The tally-sheet 26 may be pushed under the platen from the rear until its front end has passed the forward end of the apron 50 55 14. The sheet may then be seized and pulled up around the platen until it can be gripped against the latter by the feed-roll 27, as illustrated in Figures 2 and 3. The upward bend 29 in the right-hand arm 28 prevents the arm 60 from striking the shaft 32 when the roll 27 engages against the platen. This use of the roll 27 permits a heading or other data to be typed on the tally-sheet near its top edge. After the heading has been typed, the roll 27 65 may be swung upwardly to the position

shown in Figure 4 where it will be held against pins 61 by the pull of springs 62, the same that hold the roll against the platen. This desirable result is obtained by fastening one end of each spring to a pin 63 in one 70 of the arms 28, and fastening the other end of the spring to a pin 64 in the plate 25, which pins are positioned so that the springs 62 are moved across the line of the axis 30 when the roll 27 is raised from its lower to 75 its upper position. A light downward pressure of the bar 38 will raise the feed-roll 34 against the pull of a spring 65 and permit the tally-sheet 26 to be easily inserted between the feed-rolls 31 and 34. Several 80 items may be typed on the sales-slip 60 in the usual way and the platen 10 line-spaced after typing each item, without affecting the tally-sheet 26, since there are no feed-rolls holding the sheet against the platen. After all the 85 items have been typed on the sales-slip, the carriage may be moved to the left and the customer's name with the total of his purchase and any other desired memoranda may be typed on the tally-sheet 26. When more 90 than one line of data is typed on the tally-sheet, the latter may be line-spaced by manipulation of the lever 17 without affecting the sales-slip 60, since the platen 10 is not moved by rotation of the feed-rolls 31 95 and 34. The sales-slip may be removed and another one inserted without disturbing the tally-sheet 26. It can be readily seen that, if desired, carbon copies can be made of either or both the sales-slip 60 and the tally-sheet 26. 100

Variations may be resorted to within the scope of the invention, and portions of the improvements may be used without others.

Having thus described my invention, I 105 claim:

1. In a typewriting machine having a platen, a carriage, a feed-roll frame mounted on said carriage in superposed relation to said platen, a feeding couple including a stationary feed-roll mounted in said feed-roll frame above said platen and not engaging the same, a shaft, having an extension, for said upper stationary feed-roll, means associated with said extension and operable to rotate said stationary feed-roll, and a displaceable feed-roll mounted in said feed-roll frame and arranged to engage against the top side of said stationary feed-roll, a pair of arms pivotally mounted on the outside of said frame, at the rear of the pair of feed-rolls, a work-piece-holding roll mounted in the free ends of said arms, the forward portion of said arms being curved upward and over the shaft-extension and then downward below said pair of feed-rolls to engagement with said platen a short distance above the printing-line thereof, and a spring for pressing said work-piece-holding roll against said platen, said work-piece-holding roll being 110 115 120 125 130

displaceable upwardly and held out of engagement with the platen by said spring when so displaced.

2. The combination in a typewriting machine with a platen, a carriage, and a feed-roll release-lever adjacent one end of said platen, of feed-rolls arranged for engagement against the under side of the end portion of said platen opposite to said lever, ¹⁰ a frame mounted on said carriage above the end portion of said platen adjacent said lever, a stationary feed-roll mounted in said frame above said platen and not engaging the same, a pair of arms pivotally mounted ¹⁵ on the sides of said frame, a bar-like connection for the rear ends of said arms, a feed-roll mounted in the front ends of said arms and arranged for engagement against the top of said stationary feed-roll, springs ²⁰ arranged for holding the uppermost feed-roll in engagement with the other upper feed-roll, and further arranged to permit a

slight pressure on said bar-connection to separate said upper feed-rolls, and means operated by said feed-roll release-lever arranged for rotating said upper stationary feed-roll. ²⁵

3. The combination in a typewriting machine, with a platen and a feed-roll release-lever, of two rotatable feed-rolls mounted ³⁰ one above the other, means for yieldingly holding said feed-rolls in engagement with each other, the upper feed-roll being carried upon a pair of arms connected by a bail, each arm being pivoted at a point between ³⁵ said bail and said upper feed-roll, whereby depression of said bail separates said feed-rolls, the lower feed-roll being positioned above said platen and not in engagement with the same, and means operable by said ⁴⁰ feed-roll release-lever for rotating said feed-rolls to feed a work-piece therebetween.
